UNITED STATES PATENT OFFICE.

FRANK G. BREWER, OF HUNTER, NORTH DAKOTA.

VEGETABLE CUTTER.

Application filed April 12, 1922. Serial No. 551,949.

To all whom it may concern:

Be it known that I, FRANK G. BREWER, a citizen of the United States, residing at Hunter, in the county of Cass and State of North Dakota, have invented certain new and useful Improvements in Vegetable Cutters, of which the following is a specification.

This invention relates to new and useful improvements in vegetable cutters generally and more particularly to cutters for dissecting vegetables to obtain seeds therefrom.

An object of the invention is to generally improve machines of this type and especially the same for operating the movable cutters whereby it is entirely automatic in its operation.

Another object of the invention is to provide an improved hopper construction embodying simplified means for holding vegetables in a position to be operated upon, and means for preventing displacement of the vegetable from the hopper.

A further object of the invention is to provide a device of the above character which is of exceptionally durable construction, comparatively inexpensive to manufacture, and one which efficiently accomplishes its functions.

Other objects of the invention will be come apparent during the course of the following description.

In the accompanying drawings forming a part of the description and wherein like numerals are employed to designate like parts throughout the several views:

Figure 1 is a side elevation of the invention.

Figure 2 is a longitudinal section through the same,

Figure 3 is a transverse section through the machine,

Figure 4 is a perspective view of one of the stationary cutters,

Figure 5 is a perspective view of a part of the movable presser arm,

Figure 6 is a perspective view of another one of the stationary cutters,

Figure 7 is a support therefor; and

Figure 8 is a perspective view of the presser or masher arm.

In the drawings wherein for the purpose of illustration is shown the preferred embodiment of my invention, the numeral 1 designates a supporting frame in its entirety which consists of side bars 2 and end bars 3 which are connected to form a rec-

tangular frame. This frame is supported upon legs 4 depending from the corners thereof.

The hopper structure 5 includes a vertically disposed plate 6 secured between the side bars 2 at one end of the frame. This plate carries the stationary blades or cutters, one of which as shown in Figure 4 is a straight blade 7 extending from a fastening plate 8 arranged at right angles thereto so that when the plate 8 is fastened to the plate 6 by means of bolts or any other suitable fastenings, the blade 7 will be arranged longitudinally of the frame. The plate 6 also supports other blade holders 9, two of which are shown in the present structure, and each of which carries a pair of spaced upstanding arms 10 which are shouldered at their upper ends to support stationary blades 11 which are arranged transversely of the frame 1 and directly beneath the stationary blade 7. The upper ends of the arms 10 are apertured as are the blades 11, whereby they are detachably connected to the holder and can be readily removed to be sharpened. In order to hold the vegetable in position to be cut into pieces directly above the stationary blades, a pair of spring pressed plates 12 hinged at their upper edges to L-shaped supports 13. Each support has one end threaded to be received through a vertical opening in one of the side bars 2 whereby a nut can be associated therewith for securing the support in position upon its respective bar so that one arm extends vertically and the other arm 14 thereof is arranged horizontally and extends toward the plate 6 so that the free end of each horizontal arm can be supported in an end of a horizontal strap 15 secured transversely to the upper end of the plate 6. These two vegetable holding plates 12 are normally retained in downwardly converging relationship, as clearly seen in Fig. 3 by means of coiled springs 16 mounted upon arcuate link 17 slidable through upright plates 18 secured to the side bars 2. By reference to the drawing, it will be seen that these springs bear against the upright plates 18 and normally urge the lower ends of the plates 12 inwardly toward each other, so that their lower free ends normally engage opposite sides of the blade 7 to limit their inward swinging movement. A downwardly inclined and curved shield 19 is fastened to the frame in any suitable manner so as to span

the space between the holder plates 12, so that the latter, the upright plate 6 and the shield 13 form a hopper structure.

The means for pressing the vegetables onto the stationary blades consists essentially of a rotary presser arm 20 which is secured between its ends on a driven shaft 21 journalled transversely of the frame 1 in bearings 22 which are arranged substantially intermediate the ends of the supporting frame. One end of this shaft 21 extends beyond the frame and is there fastened to a sprocket 23 which is driven by a smaller sprocket 24 keyed to a shaft 25, journalled in bearings 26 carried by the end of the frame opposite the cutters. A chain 27 is of course associated with the sprockets 23 and 24 so that the shaft 25 imparts rotary movement to the shaft 21. A pulley wheel 28 is keyed to the shaft 25 to transmit movement thereto.

The presser arm 20 has its end adjacent the cutters forked as clearly shown in Figure 8 and to each arm 29 of the fork is fastened a plurality of blocks 30 which are spaced vertically to permit the arm to pass the cutters during its rotary movement.

The blocks of the two arms are arranged directly opposite one another so that a number of transverse slots 31 are provided in the presser head formed by the fork 29. As clearly shown, the blocks of the two arms 29 extend toward each other and their inner ends are spaced apart to provide the head with a longitudinally extending slot 32 adapted to receive the longitudinally extending blade 7 when the presser head is depressed. The under face 33 of each block 30 as clearly shown in Figures 5 and 8 is inclined so that the smaller ends of the tapered blocks 30 are arranged innermost and the under surface of the presser head is formed so as to center the vegetable on the cutters during the downward movement of the arm.

The opposite end of the presser arm is provided with an adjustable weight 34 to maintain tension on the drive chain 27 so that there will be pause or jerk of the presser arm upon coming in contact with the vegetables. It will be understood that the vegetable to be cut or seeded is placed in the hopper structure so that it is supported directly above the stationary blades 7 and 11 by means of the guide plates 12; the springs 16 on the links 17 acting to hold the plates 12 in a downwardly converging relationship whereby their lower free ends abut opposite sides of the stationary blade 7 as hereinbefore stated. As the presser head 29 moves downwardly for engagement with the vegetable, the arm 20 directly in back of the head 29 passes through a vertically arranged slot in the curved shield plate 19 so that the head 29 may engage the vegetable to

force the same into contact with the stationary blades 30. Due to the fact that the under sides of the blocks 30 are so formed and arranged as to provide the presser head with an inverted V-shaped longitudinally extending channel, it will be appreciated that when the head engages the vegetables resting upon the plates 12, there will be no possibility of the vegetable slipping out of engagement with the presser head so that it is positively forced down upon the stationary blades 7 and 11. As the vegetable is forced further downwardly by the presser head, the guide plates 12 separate to permit passage of the vegetable and the presser head, it being understood that the stationary blades 7 and 11 pass through the spaces between the blocks 30 of the presser head to permit complete dissection of the vegetable.

After the presser head has forced the vegetable thru the blades and freed itself of the resistance incident thereto; its natural tendency is to lurch forward, but the counter balance weight 34 comes into play to minimize this action and cause the presser arm to maintain a uniform rotation. As soon as the head passes beyond the guide plates, the coiled springs 16 on the links 17, force them inwardly until they come in contact with the stationary blade 7 which limits their further upward movement and retains them in correct position to properly receive the next vegetable or batch of vegetables placed in the hopper. Other vegetables to be cut are then placed in the hopper structure while the presser arm 20 is completing its revolution, it being understood that the rotation of the arm is regulated so that as quickly as vegetables are placed in the hopper, the presser head is descending toward the hopper to pass therethru.

The foregoing description and the accompanying drawings have reference to the preferred or approved embodiment of my invention. It is to be understood however, that such changes may be made in construction and arrangement of parts, materials, dimensions, etc., as may prove expedient and fall within the scope of the appended claims.

Having thus described and illustrated my invention what I claim is:

1. A vegetable cutter comprising a supporting frame, a plate secured thereto and rising therefrom and constituting part of a hopper structure, a pair of L-shaped supports arranged on opposite sides of the frame, each support including a vertically disposed arm secured to the supporting frame and a horizontally disposed arm supported by said first mentioned plate, a vegetable supporting plate hinged to the horizontal arm of each L-shaped support to depend therefrom, spring means associated with the vegetable supporting plates for normally retaining them in a downwardly

converging relationship to support vegetables, a blade disposed beneath said vegetable supporting plates, and means for forcing vegetables into engagement with the 5 blade and causing separation of the vegetable supporting plates.

2. A vegetable cutter including a plurality of cutter blades disposed angularly relative to one another, a presser member adapted to co-operate therewith and including a plurality of spaced oppositely disposed blocks, all of said blocks being spaced from each other to permit the passage of said blades, and the lower faces of said blades 10 being inclined to provide the underface of the presser member with an upwardly tapered recess adapted to engage a vegetable to center the same upon the cutter blades.

3. A vegetable cutter comprising a supporting frame, a plate secured thereto and rising therefrom and constituting parts of a hopper structure, a pair of L-shaped supports arranged on opposite sides of the frame, each support including a vertically disposed arm secured to the supporting frame and a horizontally disposed arm sup-

ported by said first mentioned plate, a vegetable supporting plate hinged to the horizontal arm of each L-shaped support to depend therefrom, spring means associated 30 with the vegetable supporting plates for normally retaining them in a downwardly converging relationship to support vegetables, a plurality of cutter blades disposed angularly relative to one another, a presser 35 member adapted to cooperate therewith and including a plurality of spaced oppositely disposed blocks, all of said blocks being spaced from each other to permit the passage of said blades, and the lower faces 40 of said blades being inclined to provide the under face of the presser member with its outwardly tapered recess adapted to engage a vegetable to center the same upon the cutter blades.

In testimony whereof I affix my signature in presence of two witnesses.

FRANK G. BREWER.
